DOOR RETAINER OR HOLDER

William Jennings Butts, Brunswick, Ga., assignor of one-half to Centennial Development Company, Inc., Bridgeport, Conn., a corporation of Delaware

Application July 7, 1936, Serial No. 89,443

7 Claims. (Cl. 292—343)

This invention relates to door retainers or holders.

Generally the objects of the invention are to provide an efficient, strong, durable and inexpensive door retainer or holder of light weight and simple and compact construction, which may be readily applied to operative position and which will function without injury to the door and floor to which it is applied.

Other and more specific objects and advantages realized by the invention will be apparent and readily understood from the detailed description which follows and from the accompanying drawing. In said drawing, illustrating what is at present regarded as the preferred embodiment of the invention,

Figure 1 is a perspective view showing the door retainer in its normal unsprung condition;

Figure 2 is an end elevation of the left hand end of the retainer shown in Fig. 1;

Figure 3 is a vertical section on line 3—3 of Fig. 2;

Figure 4 is a perspective view showing the retainer in a sprung or bowed condition preparatory to application to operative position beneath a door and between the lower edge of the same and the floor;

Figure 5 is a vertical section longitudinally of the retainer and transversely of a portion of the lower edge of a door to which it is applied and showing the retainer in its operative position in relation to the door;

Figure 6 is a view in elevation showing the door of Fig. 5 moved to the right along the smooth top of the holder from the position in which said door is shown in Fig. 5, and also showing the corresponding and resulting compression of the rubber foot member at the right-hand end of the holder and also illustrating the wedging action of the holder under such conditions; and

Figure 7 is a vertical sectional view through the foot at one end of a modified construction.

Referring to Figs. 1-6, the spring member 10 of the holder is a flat strip of spring sheet metal having its top surface well polished. Preferably it is clock spring steel of 80-90 carbon and of approximate dimensions of two inches in width, five inches in length and of gauge thickness of .010-.0112. This kind of metal and these approximate dimensions have been practically demonstrated to give good results.

On the underside of each end of the spring member 10, there is a leg or dependent member 12. As shown, each member 12 is formed from a

single piece of sheet metal, bent to suitable shape to constitute a transverse dove-tail recess adapted to receive a foot-member presently described. The sheet metal of each member 12 is also doubled upon itself to form a projecting flange 13 to serve as a grip for bending the door holder, as presently explained. The flange 13 of one of the leg members has a perforation 14 adapted to be engaged over a hook or other suitable projection in suspending the door holder, when not in operation, in convenient location in respect to the door with which it is to be used. Rivets 11, at opposite ends of spring member 10, pass through openings in the leg members 12, 12, to secure the same to the spring member 10. Soldering or welding, or any other suitable securing means may be used instead of the rivets.

The two feet or floor-engaging members are fastened to the two leg members 12, 12, respectively, each foot member comprising lower and upper portions 15 and 16 respectively, the upper portion having inclined side walls and fitting closely within the dove-tailed recess of its corresponding leg member 12. The bottom or floor-engaging surface of the lower portion 15 of each foot member is preferably inclined or convexly curved in a direction longitudinally of the spring member 10 and is formed with corrugations extending transversely of the member 10, said corrugations being constituted of ribs 17 and intervening grooves 18, which grooves, as shown in Fig. 1 for example, are relatively deep. The foot members 12, 12 are preferably of rubber, but may be of any suitable rubber-like material and are preferably of the approximate dimensions of one and one-quarter inches vertically (Fig. 2) and one and one-quarter inches horizontally (Fig. 2) and of an over-all length transversely to spring member 10 of two inches.

To operate the door retainer, flanges 13, 13 are gripped between the thumb and fingers of one hand (as shown in dotted lines in Fig. 4) and is sprung or bent downwardly. The holder is then inserted beneath a door at the outer end thereof and released, as shown in Fig. 5.

The spring action of member 10 presses the feet 12 against the floor and will hold the door stationary; but where the door is pushed strongly (as by a heavy wind, or by the pull of a spring-closing device) the door will slide along the bent smooth surface of member 10 to a position near or partly over one of the feet, depending upon the amount of force exerted (see Fig. 6). This movement produces a wedging action that forces the foot more firmly against the floor, increases

the frictional engagement therewith, and prevents the door from moving further or sliding the retainer along the floor.

When the retainer is applied to a door swung close to the floor, it is necessary that the height of the feet be reduced so that member 10 will not assume too great a curvature to fit between door and floor or prevent the wedging action described above. This is accomplished by giving the feet dimensions to correspond with the amount of bend given member 10 under any given door. The more member 10 is bent the more the feet will splay outwardly in engaging the floor. Under higher swung doors the reverse occurs, and the feet engage the floor near their outer ends at their taller portions.

Fig. 7 shows a modified form of the invention. Each foot comprises a core 21, preferably of wood, attached at the underside of spring member 20 (corresponding to spring member 10 of Figs. 1-6) by rivets 22. An elastic cap 23 is designed to fit over core 21 in the manner shown, and is extended to provide a finger grip. The bottom floor-engaging surface of the cap 23 is inclined with relation to the member 20, or said surface is convex and is corrugated, the same as described above in relation to the floor-engaging surfaces of the feet members shown in Figs. 1-6.

What is claimed is:—

- 30 1. In a door-holder, the combination of a spring member; two spaced metallic leg-members depending from said spring member; a foot member carried by each leg member and metallic finger-grip projections at opposite ends of the holder respectively and formed integrally with said leg member.
2. In a door holder, the combination of a spring member; and two spaced foot members depending from said spring member, each foot member having a floor-engaging surface which is approximately convex, in a direction longitudinal of the spring, and which surface is adapted under pressure to be flattened in its engagement with a floor or the like under the door and frictionally grip the same.
- 40 3. In a door holder, the combination of a spring member; and two spaced foot members depending from said spring member, each foot member having a floor-engaging surface which is approxi-

mately convex, in a direction longitudinal of the spring, and which surface is on a portion of the foot member of elastic material adapted, under pressure, frictionally to grip a floor or the like under the door, and said spring on top being free of projection or obstruction which would prevent the door from sliding up on either end of the spring to a position partly above the foot at said end.

4. In a door holder, the combination of a spring 10 member; and two spaced foot members depending from said spring member, each foot member having a floor-engaging surface which is approximately convex, in a direction longitudinal of the 15 spring, and which surface is on a portion of the foot member which is of elastic material adapted, under pressure, frictionally to grip a floor or the like under the door, and said foot also having another portion of different material.

5. In a door holder, the combination of a spring 20 member; and two spaced foot members, each foot member having an elastic floor-engaging portion adapted under pressure frictionally to grip a floor or the like under the door, and said spring on top being free of projection or obstruction which 25 would prevent the door from sliding up on either end of the spring to a position partly above the foot at said end.

6. In a door holder, the combination of a spring 30 member and two spaced foot members serving as 30 a support for said spring member, each foot member comprising a core member attached to the spring member, and a member connected with the core member and having a floor-engaging 35 surface which is approximately convex in a direction longitudinal of the spring, and which surface is adapted under pressure to be flattened in its engagement with a floor or the like under a door and frictionally grip the same.

7. In a door holder, the combination of a spring 40 member and two spaced foot members depending from said spring member, each foot member comprising a mass of resilient friction material adapted under pressure on the spring member to be distorted to conform over a substantial area to 45 the surface of a floor against which the said members may be pressed.
